UNITED STATES PATENT OFFICE.

JOEL WILSON, OF DOVER, NEW JERSEY.

IMPROVEMENT IN FURNACES FOR REDUCING IRON ORES.

Specification forming part of Letters Patent No. 145,471, dated December 9, 1873; application filed June 10, 1873.

To all whom it may concern:

Be it known that I, JOEL WILSON, of Dover, in the county of Morris and State of New Jersey, have invented certain novel Improvements on Furnaces for Reducing Iron Ore; and I do hereby declare that the following is a full, clear, and exact description thereof, reference being had to the accompanying drawings, making part of this specification, in which—

Figure 1, Plate 1, is an elevation of one side of my improved furnace. Fig. 2, Plate 1, is a section taken vertically and diametrically through the furnace from front to rear, in the plane indicated by dotted line x^1 , Fig. 4. Fig. 3, Plate 1, is a section taken diametrically through the furnace, in the plane indicated by dotted line x^2 , Fig. 4. Fig. 4, Plate 1, is a section taken horizontally through the furnace, in the plane indicated by dotted line x on Fig. 1. Fig. 5, Plate 2, is a bottom view of the flues surrounding the internal chambers, and also the retorts with the transverse flue-passages at their bases. Fig. 6, Plate 2, is a bottom view, showing the collecting-chamber which surrounds the well-hole.

Similar letters of reference indicate corresponding parts in the several figures.

This invention relates to certain novel improvements on the furnace for reducing iron ores preparatory to their being worked into manufactured iron, for which Letters Patent of the United States were granted to me bearing date the 16th day of July, 1872.

My improvements relate, first, to a new mode of conducting the heated products of combustion from a balling-furnace under the retorts, on opposite sides of the discharge-openings thereof, and into an annular flue-space outside of the retorts; second, to a mode of increasing the draft-spaces at the tops of the flues between the retorts without weakening the retorts, all as will be hereinafter explained.

The following description of my invention will enable others skilled in the art to understand it.

In the accompanying drawings, A represents the outer casing, surrounding that portion of the furnace in which are the retorts and flues, and A' represents the outer wall of that portion of the furnace through which the spent

products of combustion pass off to the chimney. The furnace-walls A and A' are cylindrical, and between the wall A and an interior circular arrangement of flues and retorts is an annular space, b, into which heat enters from an internal chamber, E, through passages n at the bottoms of the retorts B. The retorts B and flues C are arranged alternately around the central flue-chamber E, as described in my Letters Patent above referred to and represented in Figs. 4 and 5, which central chamber is provided on top with a cover, D, and at its lower termination it opens into a well-hole, G, into which the heated products of combustion are received from a balling-furnace through a horizontal flue, F, which is below the surface of the ground. Surrounding the well-hole G, above the flue F, and inclosed by the wall A', is an annular collecting-chamber, I, having an outlet, J, leading to a chimney, and also a number of inlets, h, corresponding to each descending flue C, which inlets are at the top of pipes H, that communicate with the lower ends of said flues C, as shown in Fig. 3. The pipes H surround the upper portion of the wall of the well-hole G, and form lower continuations of the flues C below the bottoms of the retorts B, so that the descending products of combustion can be carried from the upper to the lower portions of the furnace, between the spaces which are left for the removal of the ore after it has been subjected to the process of cementation. In other words, the flue-pipes H afford access to the discharge-holes d at the bottoms of the retorts, which holes are provided with gates or doors d', applied in any suitable manner.

In my Letters Patent above referred to I have the same arrangement of flue-pipes H beneath and on opposite sides of the discharge-holes of the retorts, and in said patent these pipes form external continuations of the flue C, and communicate with an annular collecting-chamber; but this chamber is located below the inlet-flue F, while in the present instance the collecting-chamber is wholly above said flue F, for a reason hereinafter explained.

The products of combustion rise through the well-hole G into the internal chamber E, and a part of these products enter the annular space b through openings e and passages n.

Most of the products rise to the top of the chamber E, and thence pass horizontally outward through short conduits *c*, and enter the upper ends of the flues C through apertures *c'*. (Shown in Fig. 3.) The products thence descend through flues C and pipes H, and enter the annular chamber I, from which they are conducted off through pipe J into a chimney, as above stated.

The upper ends of the retorts are provided with openings *a*, which allow the carbonic-acid gas formed in the process of cementation to escape, and also allow additional material to be supplied to the retorts, as occasion requires.

By locating the flue F below the annular collecting-flue I, instead of above it, as described in my Letters Patent before named, the intensity of heat in said chamber I is greatly reduced, and the flue F can be passed under the surface of the ground, which gives room to discharge the retorts directly opposite the puddling-furnace, thereby giving the use of two retorts, which could not be discharged if flue F passes through the annular chamber I on a horizontal level with it.

By means of the flues *n n*, directly under the bottoms of the retorts B, a large quantity of heat is carried to the space *b*, sur-

rounding the retorts, which thoroughly heats the ore at the bottoms and outer sides of the retorts.

By having the horizontal external conduits *c* on top of the furnace, as described, for establishing communication between the internal chamber E and the descending flues C, I obtain a good draft and afford plenty of flue-space without weakening the retorts by leaving openings between them.

Having described my invention, what I claim as new, and desire to secure by Letters Patent, is—

1. The flue F, located below the annular collecting-chamber I, and communicating with the internal chamber E, which is surrounded by retorts and flues, substantially as described.

2. The flue-passages *n n* under the retorts B, leading from chamber E into the annular space *b*, surrounding the retorts, substantially as described.

3. The external conduits *c*, forming communications between the chamber E and the upper ends of the descending flues C, substantially as described.

JOEL WILSON.
